UNITED STATES PATENT OFFICE.

WALTER F. SOMES, OF BOSTON, MASSACHUSETTS, ASSIGNOR TO WILLIAM B. MERRILL,
OF NEWTON, MASSACHUSETTS.

FIRE-CHECK.

1,294,966.

Specification of Letters Patent. Patented Feb. 18, 1919.

Application filed October 17, 1917. Serial No. 197,067.

To all whom it may concern:

Be it known that I, WALTER F. SOMES, a citizen of the United States, and resident of Boston, in the county of Suffolk and State 5 of Massachusetts, have invented new and useful Improvements in Fire-Checks, of which the following is a specification.

This invention relates to fire checks to be used in conjunction with the packings of the 10 piston rods of gas engines. More particularly the invention relates to a segmental ring fire check which shall be adjustable to take up wear.

Heretofore fire checks have usually been 15 made in the form of an integral ring which closely surrounds the piston rod at the side of the piston rod packings toward the engine cylinder. When the inner surface of such rings wears away, or when the rod itself 20 wears, or both, so that the joint between the fire check and the rod is no longer sufficiently tight, the fire check ring is discarded and a new one applied. With the segmental ring of the present invention the fire check may 25 be adjusted in the manner hereinafter described to insure a proper fit when the parts become worn.

The principal objects of the present invention are to provide a segmental fire check 30 of such construction as to form a tight barrier against the passage of combustion gases, to provide for adjustment so as to prolong the useful life of a fire check, to prevent the pressure within the cylinder from forcing 35 the fire check ring segments outwardly from the piston rod, to utilize the pressure within the cylinders to hold the ring segments against each other and the piston rod, and to prevent or lessen localized wear on the 40 piston rod and fire check due to gravity of the fire check.

In the accompanying drawings, wherein I have illustrated one specific embodiment of my invention,—

45 Figure 1 is a side view of a fire check containing the invention; and

Fig. 2 is a longitudinal central section through the casing to be attached to a cylinder and in which the fire checks are housed, parts of the checks being broken away and shown in section.

The casing C, Fig. 2, housing the fire checks and surrounding the piston rod A, is provided with suitable annular grooves and 50 packing-rings, as usual and not shown, and

may be lubricated in any desired manner. The interior of the cylinder is to the left as shown in Fig. 2, the fire checks being subjected to pressure of hot gases acting in the direction of arrow a. Each segmental fire 60 check ring 1, 2, 3, 4, is held in an internal annular recess 12 in the part of casing C nearest the cylinder.

The segments 1, 2, 3, 4, whatever their number and form, are arranged to fit together at their complemental abutting ends so as to be substantially gas-tight under the usual conditions of lubrication, the thickness of the ring and the width of the casing recess being such as also to make a tight joint 70 without employing two or more staggered segmental rings in one annular ring-space. Preferably the complemental end surfaces of the segments in mutual contact are flat, but fitting convex and concave, or other surfaces 75 may be employed without departing from my invention.

While any suitable number of segments may be employed, the particular embodiment of the invention illustrated in the figures is 80 made up of four like segments, 1, 2, 3 and 4, each segment having substantially a quadrant bearing surface and extending through somewhat more than 90° so as to fit together in overlapping relationship. For instance, 85 each segment is provided with a recess at one end and a projection 1^a at the other end fitting into the recess of the next adjacent segment, the surfaces 5 of the recesses lying preferably in a tangential direction, or sub- 90 substantially at right angles to axial planes V—V and H—H respectively near the ends 1^a of the segments. The abutting end-surfaces 6 of the projections and recesses, which limit the minimum diameter of the ring, are 95 disposed crosswise of the ring, preferably at right angles to the bottoms 5 of the recesses and parallel with the respective planes V—V and H—H. The surfaces 5, while pref- 100 erably tangential to a diameter near the joints, may not be so positioned so long as diametrically opposite joints 180° apart on the ring, whatever the number of segments, comprise lines of juncture at 5 which are parallel, so that the ring may be opened and 105 closed on a diameter by sliding these surfaces one on the other. An even number of segments is for this reason preferred.

The ends 1^a of the segments projecting into the recesses extend somewhat beyond 110

the axial planes V—V and H—H, as shown in Fig. 1, so that the extreme ends of the projections are of substantially a constant cross-section and of the same radial thickness throughout a considerable distance, the extreme ends thus being of the same thickness at points disposed on each side of an axial plane a distance equal to the distance between the ends of the projections and the 10 axial plane and substantially of the same thickness throughout a distance at the end 1^a greater than the expected alteration to compensate for wear. When the inner surfaces of the segments become worn away 15 the ends of the projections may be cut or milled off parallel to the former surface so as to reduce the internal diameter of the ring and restore the close fit between the ring and the rod which it surrounds without altering the fit at surfaces 5, 6. To avoid 20 employing any elaborate jigs or tools to accurately machine, mill or grind the ends 1^a to take up wear, I prefer to provide accurately placed holes 13 in the same relative 25 positions in each segment, in a part of the segment housed in grooves 12, so that a stack of the segments can be strung on a rod and clamped or chucked together for milling or grinding off the required amount of the 30 end 1^a.

A band spring 7 is provided to hold the segments together in the form of a ring. The spring 7 is secured to one segment by means of a screw or stud 8, and engages the 35 raised portions 9 disposed on the respective segments in the regions of the joints between them, the spring pressing against each segment only at the region of its recess. A filler or strip 10 is preferably mounted on 40 the segment disposed between the ends of the band spring so as to equalize the outer diameter of the assembled structure.

Slots 11 are provided on that face of each fire check which is disposed toward the 45 cylinder so as to permit free communication between the open space in the annular recesses 12 and the interior of the cylinder for the passage of fluid-pressure from the inner side of the ring facing the pressure to the 50 outer periphery of the ring. The outer peripheral surface of the ring 1, 2, 3, 4 being of greater area than the inner surface, leakage about the rod A tending to force the segments outwardly is overbalanced, a pressure 55 component being exerted toward the rod to hold the segments to a bearing against each other and on the rod A.

In Fig. 2 I have shown two fire checks in series, and it will be understood that any 60 suitable number of my improved checks may be employed in series or that a single check may be employed alone. While a single

check forms an effective close barrier against the passage of the burning gases, I prefer to employ at least two checks in series. 65

In order to prevent unequal wear of the rod A or the ring segments due to gravity of the ring, a counterbalance spring 15 may be provided in the lowest part of each annular recess 12, preferably being attached 70 at one end to casing C as by a driven headed pin 16 in a hole in the casing. Spring 15 is strong enough to sustain the weight of the ring 1, 2, 3, 4.

The filler 10 and the band-spring 7 form 75 a periphery for the assembled ring against which the spring 15 is effective in any rotative position of the ring, which has freedom to rotate about the piston-rod.

What I claim is:

1. A fire-check ring having a plurality of interfitting like segments, each segment having an end fitting against a complementary part of an adjacent segment, said end having one surface adapted to be cut away to adjust the diameter of the ring, the segment near said end being of substantially constant cross-section, whereby the ring may be readily altered to compensate for wear without changing the fitting relation of its other 90 complementary surfaces. 80

2. A fire-check device comprising a casing, a segmental gas-check ring therein, a peripheral band-spring attached to one segment to hold the ring assembled, and a spacer 95 between the ends of the spring to maintain the peripheral surface of the ring, in combination with a counterbalance spring in said casing adapted to act on the peripheral surfaces of said band-spring and spacer. 100

3. A segment for a segmental fire-check ring comprising ends of complementary form adapting like segments to be fitted together, one of said ends being adapted to be altered by a cutting operation, said segment being 105 provided with an opening related to said alterable end, whereby a series of such segments may be strung on a rod for simultaneous and similar alteration of each of the series of segments by a machining operation. 110

4. A fire-check ring made up of segments whose complementary ends abut and fit and thereby resist decrease in the size of the assembled ring, the joints between segments being sufficiently tight for use as a fire-check, in combination with a peripheral band spring surrounding the segments and bearing on all of the segments, whereby to hold the ring assembled with the abutting 115 ends of the segments in contact. 120

Signed by me at Boston, Massachusetts, this first day of October, 1917.

WALTER F. SOMES.
